(57) **CLAIM**

(21) Appl. No.: **29/135,470**

The ornamental design for a maximum-minimum thermometer made from aluminum, as shown and described.

(22) Filed: **Jan. 12, 2001**

DESCRIPTION

(30) **Foreign Application Priority Data**

FIG. 1 is a front elevational view of a maximum-minimum thermometer made from aluminum showing my new design; FIG. 2 is a left side elevation view of the maximum-minimum thermometer made from aluminum shown in FIG. 1, the right side elevational view being a substantial mirror image thereof;

Jul. 14, 2000 (DE) 400 06 591

FIG. 3 is a rear elevational view thereof;

(51) LOC (7) Cl. **10-04**

FIG. 4 is a top plan view thereof;

(52) U.S. Cl. **D10/57**

FIG. 5 is a bottom plan view thereof; and,

(58) Field of Search D10/57; 374/162,

374/190, 194, 208, 187, 205, 206

(56) **References Cited**

FIG. 6 is a front perspective view thereof.
